UNITED STATES PATENT OFFICE.

ROBERT R. SWANEY, OF SACRAMENTO, CALIFORNIA.

AUTOMOBILE RADIATOR.

1,417,783.

Specification of Letters Patent. Patented May 30, 1922.

Application filed December 26, 1919. Serial No. 347,472.

To all whom it may concern:

Be it known that I, ROBERT R. SWANEY, a citizen of the United States, residing at Sacramento, in the county of Sacramento, 5 State of California, have invented certain new and useful Improvements in Automobile Radiators; and I do declare the following to be a full, clear, and exact description of the same, reference being had to the accompanying drawings, and to the characters of reference marked thereon, which form a part of this application.

This invention relates to improvements in radiators, being adapted to be used for cooling the cylinder-jacket water of internal combustion engines of all kinds, whether used for automobiles, tractors, trucks, aeroplanes or similar purposes.

It is also adapted to be used for condensing purposes in connection with steam boilers and the like.

The type of radiator is that known as the honey comb type, on account of the shape of its core, the principal object of the invention being to devise a radiator of this type which will be stronger than the radiator as now constructed, and yet more flexible.

Another object is to construct and position the water passages so that the water must 30 traverse a relatively longer distance for a given height of radiator than is had with present radiators, and in which as a consequence the water is subjected to the cooling air or other medium for a longer period 35 during its passage through the radiator, and more water can therefore be adequately cooled in a given space.

The radiator passages are also arranged so that the water in passing therethrough 40 will be agitated and churned, thus alternating the layers of water thrown against the cooling surfaces and further enhancing the cooling processes.

I am also enabled to have a greater number 45 of water passages or tubes in a given width than is otherwise possible with the same width of cells or tubes.

With my radiator construction, there is no tendency for sediment to deposit or collect 50 in the water passages, which would of course

affect the circulation and cooling of the water.

A further object of the invention is to produce a simple and inexpensive device and yet one which will be exceedingly effective 55 for the purposes for which it is designed.

These objects I accomplish by means of such structure and relative arrangement of parts as will fully appear by a perusal of the following specification and claims. 60

In the drawings similar characters of reference indicate corresponding parts in the several views.

Fig. 1 is a fragmentary front elevation of a radiator constructed along my improved 65 lines.

Fig. 2 is a sectional view of the same.

Fig. 3 is a fragmentary perspective view showing the weave or method of building up the radiator sections. 70

Fig. 4 is a fragmentary sectional view of another form of water passage construction.

Referring now more particularly to the characters of reference on the drawings, 1 denotes in general a section of the radiator 75 structure, there being as many such sections as are necessary to attain the desired width of radiator, and each section being the height desired for the radiator.

Inasmuch as the results I obtain with my 80 radiator construction are due solely to the method of building up or weaving the sections, I will now describe this method.

In common with radiators of the honey comb design, the sections are each formed 85 of an endless strip of sheet metal 2 whose width is that of the radiator. In weaving a section, let us presume that the start is made at A (see Fig. 3). The sheet metal from this point extends straight for a certain distance as at B and is then bent up at right angles as at C, the length of the portion C being one-third the length of the strip B. At the end of the portion C the strip bends again parallel to the portion B 90 and in the same plane as at D, which last portion is the same length as the portion C. A right angle bend E is then made to the strip B, thus forming a square cell 3. At the point of junction of the portion E with 100

the strip B the metal 2 extends parallel to and adjacent said strip as at F, and is then bent up at right angles as at G, each such bend being of the same length as any side 5 of the cell 3. At the termination of the portion G the strip is bent at right angles and extends over the edge D of cell 3 as at H to a distance therebeyond equal to the length of one side of the cell, which length 10 it will be seen is equal to that of strip B. From this point the metal is again bent up to form a side J equal and corresponding to the side C of cell 3, and the operation repeated until the section attains a height 15 desired for the radiator.

With the bending of the portion H, a cell 20 4 is formed alongside cell 3. It will also be noted that there are three thicknesses of metal along one edge of each alternate cell, as shown at 5.

I have therefore formed a cell or section 25 structure in which each pair of cells is offset or stepped one cell from each succeeding pair, and in the same direction.

Therefore when the section is positioned 30 in a vertical plane, the outer and opposite corners of each pair of cells will lie in a horizontal plane. This makes for a very flexible construction and one which stands strains and shocks without fracture.

Each such opposite and outer edges of 35 each pair of cells is recessed as at 6, such recesses being set back from the outer ends of the cells.

The radiator as stated, is built up of a 40 number of sections, the offset cells of each section resting adjacent the corresponding cells of the adjacent section. It will therefore be seen from Fig. 2 that the recesses of 45 one section are in horizontal alinement with the sharp inner corners of the stepped cells of the adjacent section, and so on throughout, so that a staggered effect is had from top to bottom of the radiator, and a zigzag water passage 7 is formed, which causes the water 50 to be agitated or churned during the passage therethrough.

Each recess of course extends on each side 55 of the edge of the cell for a distance somewhat greater than half the length of a side, so that an open passage will always be had between adjacent recesses, as at 8.

The sections are combined in the usual 60 manner, that is, by clamping the same together, and dipping the entire structure in solder, so that all the thicknesses of metal are sealed together at both ends and for the entire width of the radiator as well, along all the abutting thicknesses as at K 65 in Fig. 3, the radiator when thus dipped presenting an unbroken appearance, as shown in Fig. 1. By arranging or positioning the cells so that they are diagonal, I obtain a greater number of water passages for a given 70 width of radiator than can otherwise be had,

and hence a greater amount of water can be cooled.

In the form of construction shown in Fig. 4, the alternate recesses 6 are dispensed with, and a proportionate width of each outer cell 70 surface merely flattened slightly as at 9, so that the adjacent section, correspondingly treated, will form therewith a zigzag water passage 10. The weave and method of binding together of this structure is the same as 75 that previously described.

With either type of construction, should a leak in any section or cell occur by accident or otherwise, it is only necessary to plug up the two opposite ends of the cell or 80 cells affected, the water passages not being affected in any way.

From the foregoing description it will be readily seen that I have produced such a device as substantially fulfills the object of 85 the invention as set forth herein.

While this specification sets forth in detail the present and preferred construction of the device, still in practice such deviations from such detail may be resorted to as do 90 not form a departure from the spirit of the invention, as defined by the appended claims.

Having thus described my invention, what I claim as new and useful and desire to secure by Letters Patent is:—

1. A honey-comb radiator consisting of a plurality of sections, each section comprising vertically disposed rows of square cells positioned to lie with their opposite corners 100 in vertical and horizontal alinement respectively, the cells of each section being fitted in with those of adjacent sections, and continuous water-passages formed between the sections through which a straight vertical line may be drawn.

2. A honey comb radiator comprising a plurality of sections, each section comprising square cells arranged in pairs, each pair being offset one cell from the adjacent pair and in the same direction whereby when the sections are set vertically the opposite corners of each pair of sections will lie in a horizontal plane, and water recesses formed in such opposite edges, set back from the outside ends thereof.

3. A honey comb radiator comprising a plurality of sections, each section comprising square cells arranged in pairs, each pair being offset one cell from the adjacent pair and in the same direction whereby when the sections are set vertically the opposite corners of each pair of sections will lie in a horizontal plane, and water recesses in such opposite edges, set back from the outside ends thereof, the sections being adapted to lie adjacent and be secured to each other along their outer edges, and the recesses formed in the outer edges of each section forming a continuous water passage.

4. A radiator comprising rectangular cells 130

positioned vertically but with their opposite corners lying in vertical and horizontal planes, each vertical row of cells having water passages formed along one set of horizontally opposed corners in vertical staggered alignment with the similar passages on the adjacent row and set back from the ends

of the cells, said recesses being made by forming the metal inwardly along said corners with the corners as central axes, where- 10 by the position of the metal so formed is reversed from its normal setting.

In testimony whereof I affix my signature.

ROBERT R. SWANEY.
